UNITED STATES PATENT OFFICE.

BERNARD LEONARD, OF MAHANOY CITY, PENNSYLVANIA.

COAL AND ROCK DRILL.

SPECIFICATION forming part of Letters Patent No. 224,300, dated February 10, 1880.

Application filed November 6, 1879.

To all whom it may concern:

Be it known that I, BERNARD LEONARD, of Mahanoy City, in the county of Schuylkill and State of Pennsylvania, have invented certain new and useful Improvements in Coal and Rock Drills; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to an improvement in rock and coal drills; and it consists in a series of ribs fastened on the outer end of the hollow tube in which the drill is operated, having cutting-points projecting beyond the tube, and also provided with a thread on their upper sides, by means of which the said tube, by being turned against the rock or coal, cuts its own way in and fastens itself, so that the drill can be effectively operated, all of which will be more fully hereinafter described.

In the drawings, Figure 1 is a vertical section of my invention. Fig. 2 is a detail view of the combined cutting and fastening ribs. Fig. 3 is a partial vertical section of the threaded sleeve with shaft, and Fig. 4 detail views of the ribs detached from the tube.

A is a tubular casing, designed to support the drill mechanism, and in contact with the rock or coal to be drilled. It is constructed with a series of holes, a, near its outer end, through which the borings may escape and relieve the drill from liability to pack. It is also provided with a set-screw, a', near its inner end, for the purposes hereinafter set forth.

b b b are a series of lugs or ribs rigidly attached to and parallel with the outer end of the tube A between the openings or holes a. Their ends project beyond the end of the tube A, and are constructed with cutting edges or points b', so that when the latter is turned they will cut and let it into the coal or rock.

The ribs b are also made tapering to their outer end on their upper side, whereon a thread, b'', is cut, and in such relation to each rib as to form a continuous thread or screw around

them all, whereby, when the tube is turned to cut its way in the rock or coal by means of the cutters b', it is at the same time fastened securely in the hole by the said thread screwing in the rock or coal. The taper of the ribs b 55 serves to wedge the tube more securely as it is screwed in.

The ribs b have formed on their outer ends the lips or flanges b⁴, which rest against the end of the casing or tube. These lips or flanges 60 increase the cutting capacity of the points b', and serve to prevent the ribs from being forced back along the casing A when the latter is being turned into the coal or rock.

I provide a further means of fastening the 65 tube in its desired position by means of a wedge, b³, which slides into a groove or channel, b⁵, formed on the outer side of the said tube parallel with and between two of the ribs b. The wedge is employed as an additional security, and is chiefly serviceable in 70 soft coal, where there is not sufficient solidity to hold the threads on the ribs b. I attach to the wedge a cord or rope, b⁶, which is carried back along the tube to any desired length, 75 and is used to draw out the wedge for the purpose of releasing the tube.

c is a threaded hollow sleeve, having on its outer end a crank-wheel, c'. c² is a shaft, which is fixed and made to turn in the sleeve 80 c. Its ends project beyond the ends of the sleeve, and are made square or other suitable shape, to receive on the inner one a drill and on the outer a crank.

c³ is a nut run on the thread of the sleeve 85 c, and made to fit in the outer end of the tube, where it is fastened by the set-screw a', when so desired, to hold the mechanism for drilling.

c⁴ is the bit, made auger-shaped, with a socket 90 on one end, which fits on the end of the drill-shaft, and having its opposite end constructed with two series of cutting-edges, c⁵, formed at right angles to its axis or center of motion, and arranged in step form, extending from the point or center c⁶ backward and outward to its 95 rim or edge, thus forming the bit with a conical-shaped end, as shown. By this construction I provide a bit that, in drilling, if a small particle of hard substance is struck and dulls the bit on one of its edges, it can readily and 100

quickly be sharpened without dressing the whole surface edge or edges of the bit, as is the case with those of ordinary construction.

c⁷ is a crank of ordinary construction, adjustable to the outer end of the shaft *c²*.

It will be readily seen I operate my device by first screwing the cutters *b'* of the tube *A* against the coal or rock, which cuts a hole just large enough to admit the cutters and receive the tube. As it is screwed in the incline or taper of the ribs tends to wedge them more securely in. After the tube is thus fastened I then insert the drill mechanism, as shown in Fig. 1, and fasten it firmly by screwing the set-screw *a'* on the nut *c³*. The crank *c⁷* is now placed on the shaft *c²*. Turning the crank *c⁷* turns the drill, which is fed by turning the sleeve in the nut *c³* by the crank-wheel *c⁶*.

For soft coal and stone I employ the ordinary shaft, in connection with my invention, composed of a bar having a thread cut on it to receive a nut similar to that of *c³*, and having both ends constructed to receive a crank or bit, so that when the shaft is run up in the nut it may be taken out and reversed and work continued without running the shaft out again.

By having a cylindrical casing with short tapering and threaded ribs *b* on its inner end, as described, I am enabled to provide a device which may be inserted to any depth into the coal or rock.

The ribs project outward from the tube and cut a larger hole, into which the said tube will easily slide. The severe strain made upon the device often breaks the hold of the screw *b²*, which necessitates the driving of the tube deeper into coal or rock. In drilling deep holes it is often necessary to keep turning the casing until it will be forced far into the coal in order to maintain its hold.

By the construction hereinbefore described I can employ a tube of any desired length,

which could be driven its whole length into the coal, the short ribs on its end serving as the retaining means.

45

It will be further seen that the casing *A* can be made of any desired length, and made to follow the drill into the coal, so that the length of screw between the nut *c³* and bit *c⁴* may be preserved at short purchase at all times.

50

The channel or groove *b⁵* is arranged between two of the ribs *b*, as shown, so that the force of the wedge, when driven in, will be exerted against the ribs on the opposite side of the tube. This arrangement prevents the tilting of the casing out of a direct line with the drill-bit when the wedge is employed as a fastening means. The ribs *b* are attached to the casing *A* by rivets or other suitable means, so that they may be removed by a cold-chisel or other device when worn and unserviceable. Other ribs may be supplied at small cost to replace those removed.

60

I am aware that it is not new in coal and rock drills to have a tapering cylinder with cutting-teeth on its end and screw-threads formed around it, and longitudinal grooves or channels formed at right angles across said screw-thread to receive the chippings or cuttings, and I do not claim such construction; but

65

What I do claim is—

As an improvement in coal-drills, the casing *A*, provided with the removable and interchangeable cutting-ribs *b b'*, substantially as set forth.

70

In testimony that I claim the foregoing I have hereunto set my hand this 22d day of October, 1879.

BERNARD LEONARD.
